RETORT FOR TREATING OIL SHALE

Filed March 9, 1925

2 Sheets-Sheet 2

FIG. 3.

Inventor:
Edward B. Roth,
By Henry F. Langland,
His Attorney.

UNITED STATES PATENT OFFICE.

EDWARD B. ROTH, OF ST. LOUIS, MISSOURI.

RETORT FOR TREATING OIL SHALE.

Application filed March 9, 1925. Serial No. 13,938.

This invention relates to retorts for treating oil shale.

In the treatment of oil shale in order to vaporize and remove the oil therefrom with commercial success and with best results various requirements must be met.

It is essential or desirable that the shale should be fed to and through the retort approximately continuously; that the oil vapors should be produced at about the lowest temperature possible and immediately removed; that the heat should be applied with nearly unvarying intensity; that the shale should be prevented from becoming gummed or agglomerated into cakes, and should be reduced to a proper degree of fineness which may be determined empirically according to the characteristics of the shale being treated; that before being passed into the retort the shale should be dried and pre-heated to a degree of temperature approximating, but preferably not quite so high as, the degree of temperature at which the first oil vapors separate from the shale and rise; that the shale should be continually agitated and propelled to different zones of progressively increasing heat; and that the vapors be withdrawn quickly from the retort and from the different zones thereof.

It is an accepted result of experience that the longer the shale is exposed to heat and the slower the heat is applied in the respective zones proportionately better results are obtained and that the vapors from some of the shale components separate and rise under the influence of lower heat than from others.

An object of the present invention is to provide an improved apparatus designed and adapted to perform all of the above mentioned operations inexpensively and with a high degree of efficiency so that the apparatus can be used commercially and profitably.

Specifically an object of the invention is to provide an improved retort for the treatment of oil shale divided into compartments subjected to a higher degree of heat progressively from the compartment which the shale first enters to the compartment from which the shale is discharged, and having improved shale propelling and agitating devices in the compartments respectively, whereby the shale is moved through all of the zones of heat and discharged from one

compartment to another, and finally from the retort.

Another object of the invention is to provide an improved retort of the character and for the purposes mentioned, comprising one or more inclined retort agitators or stirrers by which the shale is kept in motion in one or more zones of heat.

Another object of the invention is to provide an improved shale retort having an inclined rotary agitator or stirrer subjected to heat, and means for delivering the shale to be treated near the axis of the agitator or stirrer whereby, due to the novel construction of the agitator or stirrer, the shale is caused to move into and from different baffle devices and is ultimately discharged into a passage near the periphery of the agitator or stirrer which, if desired, may lead to another agitator or stirrer operating in another one of higher temperature.

Other objects will appear from the following description, reference being made to the accompanying drawings, in which

Fig. 1 is a vertical sectional view of the present invention.

Fig. 2 is a plan view.

Fig. 3 is a plan view of one of the agitators or stirrers.

In the embodiment of the invention shown the retort comprises an outer wall 1, an inner wall 2 enclosed within the outer wall and spaced therefrom, an upper end wall or cover 3 for the enclosure formed by the inner side wall 2, a lower end wall 4 for the inner enclosure, and an upper end wall or cover 5 for the outer enclosure. The lower end wall 4 and the downwardly extended portion of the wall 2 form a combustion chamber containing a burner 6 to which fuel may be supplied from any accessible source for heating the machine.

A number of inclined partitions 7, in the present instance two, are mounted in the enclosure 2, though the number of such partitions may be varied as desired. Openings 8 are provided in the partitions 7 near the wall 2 for the discharge of accumulations. Each of the partitions 7 is provided with an annular flange 9 within which the stirrers or agitators operate.

The disc 10 is mounted eccentrically within the enclosure formed by the flange 9 of the upper partition 7, being closer to the flange at the upper side of the enclosure.

than at the lower, so that a considerable space is left below the disc which space communicates through a hole 11 with a chute 12. The disc 10 is attached to the upper end of an inclined shaft 13 rotated by driving connections 14 from a drive shaft 15 extending to the outside and provided with a driving device 16. The upper surface of the disc 10 is provided with a number of baffles 17 preferably arranged in an annular series as shown in Fig. 3, though such arrangement may be varied if desired. The baffles 17 are shaped to provide inner receptacles or cups 18 and outer receptacles or cups 19, with the exception that the baffles 17 at or near the periphery of the disc 10 need not be provided with the outer receptacles or cups.

A disc 20, of construction similar to the disc 10 and having similar baffles 17 thereon, is attached to the upper end of the shaft 15 and rotated thereby and is arranged to discharge the shale into the lower part of the enclosure formed by the flange 9 on the lower partition 7. The shale passes therefrom through a hole 21 in the lower partition 7 and thence through a chute 22 to a conveyor 23 by which the shale remnants are conducted to any desired point of discharge.

A chute or passage 24 extends through the upper portion of the retort and discharges near the center of the upper agitator or stirrer so that the shale moves continually and successively outwardly on the upper disc 10, being caught in the different cups or receptacles 18 or 19 while being subjected to heat, with the result that the vapors rise and pass from the inner enclosure through holes 25 into the space between the inner and outer enclosures and thence to a point of delivery through a conduit 26.

An alternative or additional heating device is shown, the same comprising a lower steam heating coil 27 to which steam is admitted through a pipe 28 and from which the steam passes through a connection 29 to an upper heating coil 30. The heating coils 27 and 30 are below and adjacent to the lower and upper partitions 7 respectively, so that the lower compartment is subjected to greater heat than the upper compartment. By this means the shale is continuously agitated and propelled through different zones of progressively increasing heat and is prevented from becoming gummed or agglomerated into cakes, and the vapors are caused to rise and are withdrawn quickly from the retort and from the different zones thereof. A conveyor 31 may be used in connection with the chute 24 to maintain a continuous feed of shale to and through the retort.

For the purpose of receiving, condensing and discharging certain heavy vapors from the retort, I have provided a pipe 32 having a number of openings 33 into the retort

near the upper end thereof and having a number of depending pipe connections 34 opening into another pipe 35 which has several communications 36 with the intermediate portion of the retort. The connections 33 and 36 permit any condensed liquids to pass out into the pipes 32 and 35 and thence to a point of discharge through a pipe 37.

From the foregoing it will be seen that my invention consists of a retort for the treatment of shale to remove the oil therefrom in an inexpensive, efficient and profitable manner. The machine requires little attention when in operation, it being only necessary to maintain the burner 6 and the conveyors and the operating mechanism of the machine in operation. It will continue to operate for a comparatively long time without special attention or care.

I do not restrict myself to the exact constructions and arrangement shown and described, as I am aware that numerous variations may be made in the construction and arrangement of the parts without departure from the nature and principle of the invention.

What I claim and desire to secure by Letters Patent is:—

1. A shale treating retort comprising an enclosure, a plurality of inclined partitions dividing said enclosure into separate superimposed compartments having communication with each other through inclined portions of said partitions, an agitator device supported in an inclined position in one of said compartments and above an inclined portion of one of said partitions, an inclined shaft extending through said last-named inclined partition and having connection with said agitator, and means for rotating said shaft.

2. A shale treating retort comprising an enclosure, a plurality of inclined partitions dividing said enclosure into separate superimposed compartments having communication with each other through inclined portions of said partitions, an agitator device supported in an inclined position in one of said compartments and above an inclined portion of one of said partitions, an inclined shaft extending through said last-named inclined partition and having connection with said agitator, means for rotating said shaft, and means for delivering shale upon the central portion of said agitator.

3. A shale treating retort comprising an enclosure, an imperforate disk element supported in an inclined position in said enclosure, a number of baffles extending normal from said disk and having pockets in their sides toward the axis of said disk, means for discharging shale upon said disk, and means for rotating said disk.

4. A shale treating retort comprising an enclosure, a plurality of inclined partitions

dividing said enclosure into a number of compartments and having openings therethrough near their upper and lower edges, an inclined rotary disk in said enclosure above each of said partitions between said openings, baffles extending normal from said disk, means for conducting material to the central portion of the upper disk, and a passage from one of said compartments near the lower edge of the upper partition for conducting material therefrom to the central portion of the next lower disk.

5. A shale treating retort comprising an enclosure, a plurality of inclined partitions dividing said enclosure into a number of compartments and having openings therethrough near their upper and lower edges, an inclined rotary disk in said enclosure above each of said partitions between said openings, baffles extending normal from said disk, means for conducting material to the central portion of the upper disk, a passage from one of said compartments near the lower edge of the upper partition for conducting material therefrom to the central portion of the next lower disk, means forming a confined space around a part of said enclosure in communication with said enclosure, and means for conducting vapors from said space.

6. A shale treating retort comprising an enclosure having a plurality of vapor outlets, a wall forming a space into which said outlets open, an inclined partition in said enclosure having openings therethrough near its upper and lower edges, an inclined disk above said partition between said openings, baffles in connection with said disk, means for conducting material to the central portion of said disk, mechanism for rotating said disk, and means for conducting solid material from said enclosure.

7. A shale treating retort comprising an enclosure having a plurality of vapor outlets, a wall forming a space into which said outlets open, an inclined partition in said enclosure having openings therethrough near its upper and lower edges, an inclined disk above said partition between said openings, baffles in connection with said disk, means for conducting material to the central portion of said disk, mechanism for rotating said disk, means for conducting solid material from said enclosure, and means for heating said enclosure.

8. A shale treating retort comprising an

enclosure having a plurality of vapor outlets, a plurality of inclined partitions in said enclosure, an inclined disk above the central portion of each of said partitions, baffles extending upwardly normal from each of said disks, mechanism for rotating said disks, means for conducting shale to the central portion of the upper disk, means for conducting shale discharged from the upper disk to the central portion of the next lower disk, and means for heating said enclosure.

9. A shale treating retort comprising an inclined support, a flange extending upwardly from said support, a shaft extending through said support, a disk attached to said shaft in an inclined position above said support, pockets on the upper side of said disk, means for delivering material to a point near the center of said disk, means for rotating said shaft and thereby said disk to cause the material to move outwardly and downwardly as the disk is rotated, and a passage for conducting the material discharged from said disk.

10. A shale treating retort comprising an inclined support, a flange extending upwardly from said support, a shaft extending through said support, a disk attached to said shaft in an inclined position above said support, pockets on the upper side of said disk, means for delivering material to a point near the center of said disk, means for rotating said shaft and thereby said disk to cause the material to move outwardly and downwardly as the disk is rotated, a passage for conducting the material discharged from said disk, and an additional disk receiving the material from said passage.

11. A shale treating retort comprising an inclined support, a flange extending upwardly from said support, a shaft extending through said support, a disk attached to said shaft in an inclined position above said support, pockets on the upper side of said disk, means for delivering material to a point near the center of said disk, means for rotating said shaft and thereby said disk to cause the material to move outwardly and downwardly as the disk is rotated, a passage for conducting the material discharged from said disk, an additional disk receiving the material from said passage, and means for subjecting said disks to the desired degree of temperature.

EDWARD B. ROTH.
